UNITED STATES PATENT OFFICE.

S. B. SEXTON, OF BALTIMORE, MARYLAND.

STOVE.

Specification forming part of Letters Patent No. 23,716, dated April 19, 1859; Reissued January 25, 1876, No. 6,884.

To all whom it may concern:

Be it known that I, S. B. SEXTON, of Baltimore, in the county of Baltimore and State of Maryland, have invented a new and 5 useful Improvement in Stoves; and I do hereby declare that the following is a full, clear, and exact description of the same, reference being had to the annexed drawing, forming part of this specification, in the several figures of which similar characters of reference denote the same part.

Figure 1 is a front elevation of stove. Fig. 2 is a vertical longitudinal section of same. Fig. 3 is a perspective view, showing 15 cold air chamber.

My invention consists in a certain combination of parts hereinafter to be set forth, constituting an improvement in cylinder stoves constructed with a covered fuel chamber reaching nearly to the grate, so as to furnish a continued supply of fuel to support combustion in the fire chamber below and exterior to the said fuel cylinder. The 20 object of this improvement being to combine with this construction increased radiating surface and facilities for warming apartments above the location of the stove, while all the advantages of the peculiar construction as applied to a single cylinder 25 are retained. The entire combination being ornamental and well adapted for the purposes above stated.

In the drawing A is the central apartment of the stove containing the fire chamber F, and the covered fuel chamber H. On each side of this chamber F is a chamber B B', connected with the cylinder of 30

central chamber by pipes C and D, and in communication with each other by lower flue E. In the right hand chamber is a 40 damper *a*, and in pipe D a damper *b*. The exit flue *f* is over chamber B'.

Around the back portion of the aforesaid chambers is a casing R forming an air chamber in which the heat of the three chambers 45 A, B, B', has the effect of warming air which is conveyed into an upper apartment by a flue leading from the top of the chamber. The closing of damper *a* and opening of damper *b* permits the immediate exit of 50 the products of combustion. And the closing of damper *b* and opening of *a* causes the draft to pass downward through chamber B and upward through the chamber B'. Cold air passes into chamber R from the 55 rear, and, also from the front between the chambers A and B B'. Between the chambers are the water pans *p* for the evaporation of water to furnish moisture to the air.

I do not claim any of the parts of this 60 stove separately considered. But

I claim—

The covered fuel cylinder H in combination with the chambers A B B', flues C and D; and dampers *a*, and *b*, together with the 65 rear casing R constituting a cold air chamber; the arrangement being as set forth.

In testimony whereof I hereunto set my hand before two witnesses.

S. B. SEXTON.
